(57) **CLAIM**

The ornamental design for a dock for a wireless charger, as shown and described.

DESCRIPTION

FIG. 1 is a top, front and left side perspective view of a dock for a wireless charger showing our new design;

FIG. 2 is a top, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front and left perspective view of the dock for a wireless charger, shown in a first condition of use; and,

FIG. 10 is a top, front and left perspective view of the dock for a wireless charger, shown in a second condition of use.

In the drawings, the broken lines on the dock for a wireless charger depict portions of the dock for a wireless charger that form no part of the claimed design. In FIGS. 9 and 10, the broken lines showing a wireless charger with cord and mobile phone depict environmental subject matter only, and form no part of the claimed design.
